ATTORNEY

UNITED STATES PATENT OFFICE.

WILLIAM M. CASTLIO, OF MECHANICSVILLE, MISSOURI.

DESK.

SPECIFICATION forming part of Letters Patent No. 269,384, dated December 19, 1882.
Application filed March 10, 1882. (No model.)

To all whom it may concern:

Be it known that I, WILLIAM M. CASTLIO, a citizen of the United States, residing at Mechanicsville, in the county of St. Charles and State of Missouri, have invented certain new and useful Improvements in Desks; and I do hereby declare the following to be a full, clear, and exact description of the invention, such as will enable others skilled in the art to which it appertains to make and use the same, reference being had to the accompanying drawings, and to the letters or figures of reference marked thereon, which form a part of this specification. This invention relates to improvements in desks.

It consists substantially in the means I employ whereby a single motion of a certain part of the desk simultaneously locks the several other parts, as will be hereinafter fully explained, and pointed out in the claims.

In the drawings, Figure 1 is a vertical section on line $x-x$, Fig. 3. Fig. 2 is a vertical section on line $y-y$, Fig. 3. Fig. 3 is a longitudinal section on line $z-z$, Fig. 2, looking from rear of the desk; and in Fig. 4 I show detached views, somewhat enlarged, of parts of my device. Fig. 5 is a perspective of the desk with a portion of the front broken away, showing the locking device for the lid.

30 A A are the outer and B B the inner vertical sides of my desk.

a b are the drawer-compartments, provided with the proper rails $a' a'$ to receive the drawers $b' b'$, hereinafter described.

35 c are the side compartments, having the doors c' . These doors have on their inner sides the mortise c^2 . The upper side of this mortise is made large enough to receive the head of the bolt h^2 on the locking-bar, herein-40 after described, and the sides of the opening of the lower part are contracted, so as to secure the head of said bolt in the operation of the locking mechanism, hereinafter described.

d is the top of the desk, to which I hinge the lifting lid d' . To the under side of the forward portion of this lid I fix the staple d^2 , arranged in position to enter the mortise d^3 when the lid is shut down.

45 b' b' are the drawers, sliding on the rails a' 50 a' in compartments $a b$, as shown. These

drawers are constructed with the slots b^2 in the upper part of their sides, next the vertical sides B of the desk, and these slots are arranged in proper position to be entered by the pins or locking-bar, hereinafter described.

55 e is the upper or pigeon-hole compartment of the desk, extending the whole width of the same.

e' is the door, hinged at the bottom.

$e^2 e^2$ are triggers pivoted to the inner side 60 of the door e' , and arranged in proper position when turned down, as shown in full lines, Figs. 1, 2, and 3, to press on the top of the lock-bar, hereinafter described, and bear the same down and lock the several parts of the 65 desk when the door e is shut, as will be described. When the triggers are turned up, as shown in dotted lines, Fig. 3, the opening and closing of the door e' will not affect the locking-bar.

70 f is a bar or rod pivoted at z , Fig. 4, within the forward part of the desk, under the lid d' . It is provided at one end with the hook f' , extended to and working in the mortise d^3 , hereinbefore described, and its opposite end, f^2 , is 75 bent and connected to the bar g , as will be described.

g is a bar arranged next the side B in upper part of compartment a . This bar is pressed rearward by a spring, g' , arranged and bearing between the forward part of the said bar g and inner side of the front of the desk. The rear end of the bar g is beveled, and is engaged by the beveled side of the projection on the main locking-bar, as will be described. Near 80 the forward part of the bar g , I cut a mortise, g^2 , in which the end f^2 of the rod f presses, whereby the said rod f and bar g are connected.

85 h h are the lock-bars. They are arranged 90 within the compartments $c a$ and $c b$, next the sides B, and extend from near the bottom of the desk to within the pigeon-hole compartment e . These rods stand on the springs h' , which support them up to the position shown 95 in Figs. 1 and 3 when they are not pressed down by the triggers e^2 , as will be described.

100 $h^2 h^2$ are bolts formed with suitable heads, h^3 h^3 , adapted to enter the mortises c^2 in doors c' and lock the said doors, as will be described.

*h*⁴ are pins fixed to the side of the bar *h*, and arranged in proper position to enter the slots *b*² in sides of drawers *b*' and lock the drawers when the bar *h* is pressed down, as will be described.

*h*⁵ is a projection on forward part of the bar *h*, next the beveled end of bar *g*, and the forward part of this projection is beveled correspondingly to and bears against the beveled end of the bar *g*, and is constructed, as will be seen, to operate, when the bar *h* is pressed down, to force the bar *g* forward, which carries with it the end *f*² of the rod *f*, and the said rod *f* being pivoted, this motion carries the hook *f*' forward into the mortise *d*³, and into the staple *d*² on the lid *d*' when the said lid is shut down.

In the operation of my device, when the several parts are in the position shown in Fig. 1 and it is desired to lock them I close the door *e*'. This carries the triggers *e*² against the top of bar *h*, forcing downward the said bar with its bolts *h*², pins *h*⁴, and the beveled projection *h*⁵, the said projection pressing the bar *g* forward. Thus the head *h*³ of bolt *h*², being within the upper end of mortise *c*², is pressed down between the contracted sides of lower part of said mortise and secures the doors *c*'. The pins *h*⁴ press down in the slots *b*² in top of drawers and lock the same, and the bar *g*, being pressed forward by the projection *h*⁵, carries the end *f*² of the rod *f*, which forces the hook *f*' into the staple *d*² on lid *d*', and the said lid is securely locked.

It will be seen that by turning one of the triggers up, as shown in dotted lines, Fig. 3, the drawers on one side of the desk can be locked and the others remain unlocked, and by connecting the staple *d*² so that it may be turned up against the under side of the lid I can lock the lid or not, as desired.

Having thus described my invention, what I claim, and desire to secure by Letters Patent, is—

1. The combination, with the desk having drawers *b*', and the upper compartment, *e*, and the door *e*', hinged to close the compartment *e*,

of the bar *h*, provided with pins arranged to engage and lock the drawers *b*', and having its upper end projected into the compartment *e*, and the triggers *e*², placed on the inner side of the door *e*' and adjustable to engage or clear the projected upper end of bar *h*, substantially as set forth.

2. The combination, substantially as hereinbefore set forth, of the drawers *b*', constructed with slots *b*², bars *h*, provided with pins *h*⁴ and bolts *h*², constructed with heads *h*³, doors *c*', having the mortises *c*² on their inner sides, the lower sides of the opening of said mortises being contracted to secure the head *h*³ on bolt *h*², door *e*', and trigger *e*², as and for the purposes set forth.

3. The combination, substantially as hereinbefore set forth, of the lid *d*', provided with staple *d*², rod *f*, having hook *f*' working in mortise *d*³ and connected to bar *g*, bar *g*, supported by spring *g*' and having its rear side beveled, bar *h*, supported on spring *h*' and provided with projection *h*⁵, arranged to bear on the beveled end of rod *g*, and means for depressing the bar *h*, as and for the purposes described.

4. The combination of the drawers *b*', having slots *b*², bars *h*, having bolts *h*² and pins *h*⁴ and beveled projection *h*⁵, doors *c*', having mortises *c*², doors *e*', having triggers *e*², bar *g*, connected to rod *f*, rod *f*, pivoted and provided with hook *f*', and lid *d*', provided with staple *d*², substantially as and for the purposes set forth.

5. The combination, substantially as described, of the doors *e*', constructed with mortises *c*², having the lower sides of their opening contracted, as shown, the bar *h*, provided with pin *h*², having head *h*³, and means for operating the bar *h*, as set forth.

In testimony whereof I affix my signature in presence of two witnesses.

WILLIAM M. CASTLIO.
